UNITED STATES PATENT OFFICE

JOHN REGGITS, OF BOONTON, NEW JERSEY

TOOL FOR FASTENING SASH WEIGHT CORDS

Application filed October 22, 1931. Serial No. 570,459.

This invention relates to tools for securing metal to fabric material and more particularly to tools of the type of pliers, having for its object to provide a construction simple in parts and more efficient in operation than those heretofore proposed.

With these and other objects in view the invention resides in the novel details of construction and combinations of parts as will be disclosed more fully hereinafter and particularly pointed out in the claims.

Referring to the accompanying drawing forming a part of this specification in which like parts are designated by like numerals in all the views,—

Fig. 1 is a side elevation of a pair of pliers made in accordance with this invention;

Fig. 2 is a side view of the same pliers the jaws of which are now shown in open position about to act upon a metal clamp;

Fig. 3 is an end view of the jaws in open position;

Fig. 4 is a view similar to Fig. 1 but showing the pliers in full engagement with a metal clamp; and

Fig. 5 is a perspective view of a securing clamp which has been acted upon by the pliers, said clamp being illustrated as securing the end of a sash weight cord.

This invention contemplates a tool adapted to close a metallic clamp upon fabric in order to hold one part of the fabric relative to another. In illustrating the invention the tool has been shown as constituting a pair of pliers, and the fabric is shown as comprising the usual woven cord used for suspending the weights of window sashes. It is to be understood, however, that other modifications of the invention may be as well covered by the principles involved in this specific plier modification, the principal feature residing in the dual function of rolling one part of the metal clamp with respect to another part, and, after rolling action is completed, impressing portions of the metal clamp into the fabric being secured thereby.

In the drawing the pliers are shown as comprising two jaws 1 and 2 pivotally joined as at 3, the jaw 1 extending beyond said pivot into a handle portion 4 the extreme end of

which is bevelled and more or less sharpened to provide a screw-driver edge 5. The other jaw 2 is likewise extended to form the handle portion 6 the extreme end of which carries a link 7 adapted, when the pliers are closed, to pass over the screw-driver end of the other handle and engage a notch 8 in the handle 4 for locking the pliers in closed position. A spring 9 is interposed between the handle portions.

The jaw 2 is broadened as clearly indicated in Fig. 3 and terminates in a rounded end 10 of a radius equal substantially to the thickness of the jaw. The inner face of the jaw is concavely formed to provide a groove as indicated at 11 and extending from this concave face in a direction toward the other jaw is a pair of sharpened prongs indicated at 12, said pair being spaced one near each side extremity of the jaw.

The other jaw 1 is somewhat similarly formed, in that it has a rounded end 13 and a concave inner jaw surface providing the groove 14 the inner edges of both grooves being disposed equal distances from the pivot 3. However, the radius of curvature of the rounded end 13 is much less than the radius of curvature of the end 10 of the other jaw, and the jaw 1 is longer than the jaw 2. Also the radius of curvature of the groove 14 is greater than the radius of curvature of the groove 11, each groove extending to the extreme end of its jaw providing thereby a work manipulating edge, whereby, as will be readily seen from Fig. 1, the extremity of the jaw 1 overlies the extremity of the jaw 2; in other words, the two jaw extremities overlap.

The inner concave surface 14 of jaw 1 is provided with a single sharpened prong 15 at its mid-point, and thus is in staggered relation to the prongs 12 of the other jaw. It is also to be observed that the prongs 12 and 15 are so disposed in their respective jaws that, when said jaws are closed, all prongs will be in a common plane, and the inclination of this common plane is substantially 45° to a plane passing longitudinally through the center of the pliers and including the axis of the pivot 3. Each jaw is provided

with similar concave surfaces or grooves 16 and 17 disposed between the pivot 3 and the aforementioned concave surfaces 11 and 14, both of the concave surfaces 16 and 17 being of the same radius. Thus, there is established between the pair of concave surfaces of each jaw face an abutment (indicated in Fig. 2 at 18) contacting the similar abutment of the other jaw to limit the closing ability of the jaws, and thereby causing the grooves 16 and 17 to establish a closed passage 19 when the jaws are closed. Lastly, all of the concave surfaces 11, 14, 16 and 17 are cylindrically formed, the axis of curvature being parallel to the axis of the pivot 3, and therefore at right angles to the plane of the pliers as a whole.

In operation the pliers are used with a cord-clamping member generally indicated in Fig. 5 by the numeral 20 and which is adapted to secure firmly the end 21 of a sash weight cord to the main body portion 22 thereof after the latter has been passed through the eye 23 of a weight 24, thus obviating the necessity of tying plural knots in the cord and leaving a cord-end protruding from the last knot, which end is very apt to cause displacement of the sash weight in the window frame, resulting in banging of the weight as it trundles up and down. The use of this clamp further obviates the catching of the enlarged knot heretofore employed, by furnishing a secure fastening of small dimension and having no extending obstructions to engage with nails etc. in its travel up and down with the sash weight.

The clamp 20 is made of tin or other thin pliable metal and is generally triangular in shape, or rather it has a main flat body portion 25 (see Fig. 2) which is triangular, and along each longitudinal edge of this body portion there is formed a channel of circular cross section as clearly indicated at 26, the clamp as furnished having a relatively wide opening indicated at 27 across the mouth of the channel and of a dimension to readily receive therethrough the round sash weight cord.

After the cord has been looped through the eye of the sash weight, the free end of the cord is laid in one of the open channels, and then this channel is inserted between the jaws of the pliers, the longer or overlapping jaw being placed against the main body portion 25 of the clamp between the two channels. As the jaws are brought together, the relatively sharp edge 28 of the longer jaw will engage the angle between the main body portion and the cord filled channel, and then the other jaw will advance against the free edge portion 29 of said channel. Further pressure through the jaws of the pliers will then cause the edge 30 of the underlying jaw 43 to roll the free edge side of the channel over

the sash weight cord and ultimately bring said edge of the channel against the main body portion 25, with the cord more or less tightly encompassed by the wall of the channel.

During this rolling action the channel will have occupied a position between the prongs 12, 15 and the extreme ends of the plier jaws but, after the channel edge has been sufficiently rolled, the pliers are shifted slightly to bring the rolled over portion of the clamp further into the jaws. Then the pliers are squeezed tightly as a result of which the prongs 12 and 15 will penetrate the thin metal of the rolled over channel and form inwardly extending burs positively engaging the fabric of the cord to prevent longitudinal movement thereof in the closed channel. The main body portion 22 of the cord is then inserted in the other open channel of the clamp and the pliers used in a similar manner to first roll the channel into closed position about said body portion and then to cause its prongs to penetrate the wall of the channel to form burs extending into said main body portion, thereby completing the fastening of the sash weight with respect to said cord, see Fig. 4.

The screw-driver end of these pliers will be found very useful in removing the runner strips holding the sash relative to the window frame, as well as for other purposes. The hole 19 formed by the concave surfaces 16 and 17 will be found useful for confining any portion of the sash weight cord, especially when the handle portions of the pliers are locked by the link 7. For example when applying new cords, and after cord and weight have been secured together, it is quite necessary that the free end of the cord be kept from passing over the pulley and dropping down interiorly of the window frame. This may be readily prevented by inserting a bight of the cord in one of the grooves such as 16, then bringing the free end of the cord between the prongs 12, 15, and then pressing the pliers firmly together and latching them with the link 7, as a result of which the end of the cord will be secured by the penetrating prongs and the main body portion of the cord will lie in the opening 19. In this arrangement the pliers will assume a position across the periphery of the sash cord pulley and prevent the loss of the end of the cord by being yanked into the window frame by the weight.

It is obvious that those skilled in the art may vary the details of construction as well as arrangements of parts without departing from the spirit of the invention, and it is therefore not desired to be limited to the foregoing except as may be required by the claims.

What is claimed is:—

1. In a tool of the character described the combination of work receiving jaws having

overlapping ends; the end of each jaw tapered to provide a sharp work engaging edge; a groove in the working face of each jaw meeting a work manipulating edge; and work penetrating members within said jaws.

5 2. In a tool of the character described the combination of work receiving jaws having overlapping ends; the end of each jaw tapered to provide a sharp work engaging edge; a groove in the working face of each jaw meeting a work manipulating edge; and work penetrating members within the grooves of said jaws.

10 3. In a tool of the character described the combination of work receiving jaws, the face of each jaw provided with a cylindrically formed groove, the groove of one jaw formed by a radius greater than the radius of the groove of the other jaw, each groove formed 15 at the extreme end of its jaw providing work manipulating edges, said edges overlapping; and work penetrating members within said grooves.

20 4. In a tool of the character described the combination of work receiving jaws, the end of each jaw tapered to provide a sharp work manipulating edge, the ends adjacent said edges adapted to overlap when the jaws are closed; and work penetrating members within 25 said jaws.

30 5. In a tool of the character described the combination of work receiving jaws having overlapping ends formed by intersecting arcuately formed surfaces, and work penetrating 35 members disposed within said jaws to lie in a common plane substantially parallel to the plane of the overlapping surfaces of said jaws.

30 In testimony whereof I affix my signature.
JOHN REGGITS.
